6 Claims. (Cl. 24—227)

This invention relates to a hook joint for fasteners for clothes, particularly for waistband fasteners of the type comprising a hook and an eye.

Hook-and-eye fasteners are known, which are secured to the fabric by prongs, which are pierced through the fabric and preferably bent against a backing plate. In these fasteners, the hook member comprises a baseplate carrying a reversely bent hook portion. The baseplate carries also the prongs, which are pierced through the fabric and reversely bent against the backing plate. In these known fasteners, the hook portion tends to be forced against the baseplate, particularly in the ironing press and must be bent open so that it can be inserted into the eye member.

In the hook joint according to the invention, this disadvantage is avoided in that a crosspiece which extends transversely to the hook portion and serves for engaging the fabric is offset adjacent to the aperture of the hook portion and, if desired, on both sides of the hook portion and merges with the hook portion. The hook portion extends from the region where it merges with the crosspiece freely over said crosspiece. The backing plate is preferably oppositely offset in the region in alignment with the offset crosspiece. Such a hook member has no reversely bent edge and can no longer be compressed. Besides, it is flatter than the previously known hook members.

The offset crosspiece may be provided with a struck-off prong, which has been cut from the hook member in the direction in which the hook portion is inserted, and/or the hook member may comprise one or more prongs, which have been struck off in the direction opposite to the direction in which the hook portion is inserted. The last embodiment is capable of taking up particularly high tensile stresses. Besides, the offset crosspiece may be provided with prongs which have been struck off from the transverse direction of the hook portion and extend on both sides thereof, or such prongs may be disposed on both sides of the hook and inclined to the longitudinal direction of said hook.

Finally, the hook portion, is defined by a V-shaped strip having a central opening and thereby defining a tongue which projects above the offset crosspiece. This will result in a particularly flat and esthetically desirable form of the hook portion.

Various embodiments are shown by way of example in the accompanying drawing, in which

FIGS. 1 to 3 are perspective views showing a first embodiment of a hook-and-eye fastener provided with a backing plate.

FIGS. 4 and 5 are central sectional views taken through the hook member and the backing plate assembly of the embodiment shown in FIGS. 1 and 2.

FIGS. 6 and 7 are side and end elevation views showing the hook member of FIG. 1.

FIGS. 8 and 9, respectively, are a central sectional view and an elevation showing another embodiment of the hook member.

FIGS. 10 and 11, respectively, are a central sectional view and an elevation of the backing plate for use with the hook member of FIGS. 8 and 9.

FIGS. 12 and 13, respectively, are a central sectional

2

view and an elevational showing two further embodiments of hook members.

FIGS. 14 and 15, respectively, are a central section view and an elevation of the backing plate for use with the hook member of FIGS. 12 and 13.

In the first embodiment illustrated in FIGS. 1 to 7, the hook member comprises a hook portion 1 which is in the form of a tongue constituted by a V-shaped strip member having a central opening. The strip 1 has base portions 1' which are joined by an offset crosspiece 2. The crosspiece 2 is deformed downwardly with respect to hook portion 1 and between the base portion 1' thereof of a prong 3 extends from the crosspiece 2 at an end thereof closer to the free end of the hook portion 1. The hook portion 1 extends over the crosspiece 2. At the rear end of the base portion 1' of the hook portion, the prongs 4 and 5 have been bent downwardly. The prongs 3 to 5 are then pierced through the fabric 6 and bent against a backing plate 7, which is formed with holes 8, 9, and 10 forming passages for the prongs, as is shown in FIGS. 1 and 2. The backing plate 7 is deformed upwardly at 11 between the holes 8 to 10 to provide sufficient space for receiving the prongs. The hook portion 1 is received by a known eye 12, which is secured to the waistband fabric 16 and provided with piercing prongs 13, 14 and a backing plate 15. This is shown in FIG. 3. FIGS. 4 to 7 show in section and elevation the hook member 1 and the backing plate 7 of the first embodiment with projection lines a, b, and c. As is apparent from these figures, the curved peripheral rim 7a of the backing plate 7 extends around the periphery 1a of the hook portion 1, the height of the rim 7a corresponding at least to a portion of the free width between the backing plate 7 and the tongue 1 which form jaws for engaging the eye 12. The crosspiece 2 extends downwardly with respect to the tongue 1, and the backing plate 7 has an upwardly deformed portion 11. The deformed portion 11 of the backing plate 7 defines a space therebeneath which corresponds approximately to the thickness of the prongs to enable accommodation thereof with the outline of the backing plate.

In the second embodiment shown in FIGS. 8 to 11, the hook member is formed with tongue 17 and crosspiece 18 from which extend piercing prongs 19 to 21. Between the base portions 17' of tongue 17 the crosspiece 18 is deformed downwardly. The prong 19 is disposed at the forward end of crosspiece 18 and extends downwardly. The prongs 20 and 21 are formed on both sides of the crosspiece 18. The backing plate 22 is provided with corresponding passage openings 23 to 25 and upwardly offset deformed portions 26 between said openings.

In the third and fourth embodiments shown in FIGS. 12 to 15, the hook member is formed with tongue 27 and crosspiece 28 from which extend piercing prongs 29 to 31. The crosspiece is deformed downwardly between the base portions 27' of the tongue 27. The prong 29 is disposed at the rear of crosspiece 28 and the prongs 30 and 31 are formed at both sides of the crosspiece 28. The backing plate 32 has corresponding passage openings 33 to 35 with intervening, upwardly directed offset portions 36. The lateral prongs 30, 31 may be inclined, as is indicated in dash-dot lines in FIG. 13 at 30' and 31'. In this case a backing plate 32' with inclined passage openings 34' and 35' is used, as is also shown in dash-dot lines in FIG. 15. As is apparent from FIG. 15, the periphery 27a of the hook portion 27 is located within the rim 32a and may vary, as with respect to rim 32a, or be substantially uniform, as with regard to rim 32'.

What I claim is:

1. A hook fastener adapted for being attached to material and engaged with an eye, said fastener comprising a hook member including a tongue constituted by a

V-shaped strip member defining a hook portion, a cross-piece member connected to the strip member at the spaced ends thereof, said crosspiece member being deformed and having a portion offset with respect to said hook member such that the latter projects thereover, and prongs extending from said crosspiece member in the same direction in which the crosspiece member is offset from the hook portion, a backing plate, said backing plate having openings for receiving said prongs which are inserted through material and bent over the backing plate to secure the hook member to the backing plate with the material interposed therebetween, said backing plate including a deformed portion proximate said opening extending towards the hook member and defining a space for the accommodation of the prongs.

2. A fastener as claimed in claim 1 wherein said backing plate comprises a peripheral rim which extends in the same direction as said deformed portion thereof.

3. A fastener as claimed in claim 1 wherein the space defined by said deformed portion is approximately equal to the thickness of the prongs.

4. A fastener as claimed in claim 1 wherein said tongue defines a central opening, said offset portion of the cross-piece member being limited to the transverse extent of the central opening.

5. A fastener as claimed in claim 4 wherein said strip has base portions which merge with the crosspiece member.

6. A fastener as claimed in claim 1 wherein said deformed portion of the backing plate and the offset portion of the crosspiece member are in alignment with one another.
